UNITED STATES PATENT OFFICE.

JOSEPH HARRIS, OF CHICAGO, ILLINOIS, ASSIGNOR TO WILLIAM H. MINER, OF CHAZY,
NEW YORK.

DRAFT-RIGGING FOR RAILWAY-CARS.

1,223,870.

Specification of Letters Patent. Patented Apr. 24, 1917.

Application filed September 2, 1915. Serial No. 48,598.

To all whom it may concern:

Be it known that I, JOSEPH HARRIS, a citizen of the United States, residing at Chicago, in the county of Cook and State of Illinois, have invented a certain new and useful Improvement in Draft-Riggings for Railway-Cars, of which the following is a full; clear, concise, and exact description, reference being had to the accompanying drawings, forming a part of this specification.

This invention relates to improvements in draft riggings for railway cars.

One object of the invention is to provide a draft rigging wherein the cushioning medium is actuated in the same direction upon either inward or outward movement of the draw-bar.

Another object of the invention is to provide a draft rigging wherein the yoke or yoke acting member is moved forwardly under both buff and draft.

Another object of the invention is to provide a draft rigging wherein a spring action only is obtained under draft and a combined spring and friction action under buff.

Further objects of the invention are to provide a draft rigging so arranged that the size and weight of the cheek plates are reduced, and to minimize the number of necessary parts.

In the drawing forming a part of this specification, Figure 1 is a vertical longitudinal sectional view taken centrally of the gear and showing the parts in normal position. Fig. 2 is a view similar to Fig. 1 but showing the position of the parts under full buff. Fig. 3 is a view similar to the preceding figures but showing the position of the parts under draft. And Fig. 4 is a sectional view taken on the line 4-4 of Fig. 1.

In said drawing, 10-10 denote the center sills to each of which is secured a single stop casting or cheek plate 11 having a pair of vertically extending shoulders 12-12 spaced apart sufficiently to receive the end of a heavy stationary abutment 13, the abutment being slipped in from the under side 50 of the sills after it has been assembled with the yoke as hereinafter described.

The draw bar 14 is provided with the usual upper and lower shoulders 15-15 with which coöperate corresponding in-turned gibbs or shoulders 16-16 formed on the cast yoke A. The yoke A comprises two

like members 17-17, each of which has upper and lower arms 18-18, vertical portion 19, a side wall 20 at the front end thereof and upper and lower integral wedges 21-21. The two members 17-17 are held together by bolts 22-22 extending transversely through suitable perforated ears 23. The yoke A encircles the abutment 13, as shown, and interposed between the abutment and the rear end of the yoke A is a heavy spring 24 which, as shown, comprises an outer heavy coil and an inner light coil. On the front side of the abutment 13 is provided a pair of slidable combined friction shoes and wedge blocks 25-25. Each of these members 25 has a rear face 26 slidable upon the front face of the abutment 13, an outer inclined wedging face 27 coöperable with the adjacent wedge 21 of the yoke, and inner wedge faces 28-28 coöperable with correspondingly arranged wedge faces 29 formed on the inner end of a wedge block 30, having a stud 31 seated in a suitable recess in the rear end of the draw-bar.

The operation is as follows:

Upon inward movement of the draw-bar, the wedge block 30 will move rearwardly and simultaneously force the members 25-25 laterally. This lateral movement of the members 25 will in turn force the wedges 21 and hence the yoke A, forwardly, there being a slidable connection between the yoke and draw-bar, as will be understood. The forward movement of the yoke A will compress the spring 24 inasmuch as the forward end of the latter is held against the stationary abutment 13.

From the foregoing, it will be seen that there is a combined spring and friction action upon inward or buffing movement of the draw-bar, the friction being obtained between the sets of surfaces 28-29; 21-27; and 26 and the front face of the abutment 13. In draft, the draw-bar shoulders 15 will engage the yoke gibbs 16 and compress the spring 24, as will be understood. In this action of the gear the wedges and wedge blocks do not come into play.

From the preceding description, it will be seen that I provide a gear wherein a comparatively easy spring action only is obtained under draft and a larger combined spring and friction capacity under buff. Furthermore, I am enabled to use smaller and lighter cheek plates than are now em-

ployed inasmuch as only a single plate is required, and the arrangement is such that any M. C. B. draw-bar may be employed without the necessity of using rivets or 5 coupler keys.

I am aware that many changes and variations may be made in the details of construction and arrangement of parts, and I do not wish to be limited to the specific construction herein shown and described inasmuch as the same is merely illustrative.

Stated in a broad manner, the invention differs from the prior art, so far as I am aware, in providing means for translating 15 a force in one direction to a force in the opposite direction during one action of the gear, with the result that either an inward thrust or an outward pull is applied to the shock absorbing medium always in the same 20 direction. I, therefore, contemplate all changes and modifications as fairly come within the scope of the claims appended hereto.

I claim:

25 1. In a draft rigging, the combination with a draw-bar, a cushioning medium, and a yoke movable with the draw-bar in draft, of means co-acting with the yoke for moving the same forwardly upon rearward 30 movement of the draw-bar.

2. In a draft rigging, the combination with a draw-bar, a yoke, a fixed abutment and a cushioning medium between the abutment and yoke, said yoke being movable in 35 the same direction to actuate the cushioning medium upon both inward and outward movement of the draw-bar.

3. In a draft rigging, the combination with draft sills, a member stationary relative thereto and a cushioning medium, of a draw-bar, a yoke, means for pulling the yoke in unison with a draw-bar upon forward movement of the latter, and means for moving the yoke forwardly upon rearward- 40 movement of the draw-bar.

45 4. In a draft rigging, the combination with a yoke, draw-bar, fixed abutment, and a cushioning medium, of devices interposed between said draw-bar, abutment, and yoke for translating inward pressure from the draw-bar to an outwardly directed force on the yoke.

50 5. In a draft rigging, the combination with a draw-bar, friction elements, a spring, and means for actuating the friction elements upon rearward movement only of the drawbar, said spring being compressed in the same direction upon either inward or outward movement of the draw-bar.

60 6. In a draft rigging, the combination with a draw-bar, of a yoke having inclined friction surfaces, friction blocks coöperable therewith, said blocks being operated from

the draw-bar upon inward movement only of the latter, a fixed abutment against which 65 said blocks bear, and a spring.

7. In a draft rigging, the combination with draft sills, draw-bar, yoke, fixed abutment, and spring located on one side of said abutment, of a plurality of friction devices 70 disposed on the opposite side of said abutment and coöperable therewith.

8. In a draft rigging, the combination with a fixed abutment, a yoke having wedge 75 acting faces disposed on one side of said abutment, a spring disposed on the opposite side of said abutment and acted upon by said yoke, a plurality of friction devices coöperable with said wedge acting portions of said yoke, and a draw-bar for actuating said 80 friction devices upon only rearward movement of the draw-bar.

9. In a draft rigging, the combination with draft sills and a fixed abutment mounted thereon, of a draw-bar, a yoke movable 85 with said draw-bar under draft, a spring interposed between said abutment and the rear end of said yoke, the latter having wedge acting portions on the interior thereof, a pair of wedge blocks coöperable therewith and a wedge at the rear of said draw-bar coacting with said blocks.

10. In a draft rigging, the combination with a draw-bar and yoke, the draw-bar being movable inwardly of the yoke, a fixed 95 abutment, a spring interposed between said abutment and yoke, and wedge members interposed between the draw-bar, abutment, and yoke for forcing the yoke outwardly upon inward movement of the draw-bar. 100

11. As an article of manufacture, a yoke for draft riggings consisting of two members adapted to be detachably secured together and, when secured together, forming a hood to slidably receive a draw bar butt, 105 said yoke having integral wedges on the inner faces of the arms thereof, said wedges being located opposite each other.

12. In a draft rigging, the combination with draft sills, a member stationary relatively thereto, and a cushioning medium on the rear side of said member, of a draw bar, devices coöperable with said draw bar and movable forwardly with the latter in draft, said devices acting upon the rear end of the 110 cushioning medium during said draft movement, and means interposed between said draw bar, stationary member, and devices for translating inward pressure from the draw bar to an outwardly directed force on 115 said devices.

In witness that I claim the foregoing I have hereunto subscribed my name this 14th day of August, 1915.

JOSEPH HARRIS.
